CLAIM

The ornamental design for a foldable workbench as shown and described.

DESCRIPTION

FIG. 1 is a front perspective view of a foldable workbench, showing my new design;

FIG. 2 is a top perspective view thereof;

FIG. 3 is a front elevational view thereof;

FIG. 4 is a rear elevational view thereof;

FIG. 5 is a left side view, the right side view being a mirror image of FIG. 5;

FIG. 6 is a top plan view thereof;

FIG. 7 is a partial enlarged view of FIG. 1;

FIG. 8 is a partial enlarged view of FIG. 1;

FIG. 9 is a partial enlarged view of FIG. 1;

FIG. 10 is a partial enlarged view of FIG. 1;

FIG. 11 is a partial enlarged view of FIG. 2;

FIG. 12 is a partial enlarged view of FIG. 2;

FIG. 13 is a partial enlarged view of FIG. 2;

FIG. 14 is a partial enlarged view of FIG. 3;

FIG. 15 is a partial enlarged view of FIG. 3;

FIG. 16 is a partial enlarged view of FIG. 4;

FIG. 17 is a partial enlarged view of FIG. 5;

FIG. 18 is a front perspective view of the foldable workbench in a folding state; and,

FIG. 19 is a partial enlarged view of FIG. 18.

The broken lines in the figures are for the purposes of illustrating portions of the foldable workbench, which form no part of the claimed design.

The dash-dot-dash lines are for annotating enlarged views, and form no part of the claimed design.
